United States Patent Office.

JOHN D. RICHARDS, OF MUSCATINE, IOWA.

Letters Patent No. 94,647, dated September 7, 1869.

IMPROVEMENT IN PROJECTILES.

The Schedule referred to in these Letters Patent and making part of the same.

To all whom it may concern:

Be it known that I, JOHN D. RICHARDS, of Muscatine, in the county of Muscatine, and State of Iowa, have invented a new and valuable Improvement in Projectiles; and I do hereby declare that the following is a full, clear, and exact description of the construction and operation of the same, reference being had to the annexed drawings, making a part of this specification, and to the letters and figures of reference marked thereon.

Figure 1, of the drawings, is a vertical section of my invention.

My invention relates to projectiles; and

It consists, mainly, in a novel combination and arrangement of devices by means of which a vastly destructive missile is produced, at less cost than is usual with such devices.

The letter A, of the drawings, represents the main part or cylinder of my shell, and letter B is a representation of a hollow cap, arranged upon the cylinder A, as shown.

The letter C represents a rod, passing from the bottom of the shell to the top thereof, made hollow from the bottom to the point in the cap, indicated on the drawings.

The letters a represent small apertures through the rod C, by which fire is communicated to the hollow chambers of parts A and B respectively.

The letter H represents a leaden cap, bent over the bottom of the shell. It consists of a thick sheet of lead, made larger than the case of the shell, and has its edges turned over said case, in the manner shown.

The lower end of rod C has a thread on its surface,

and I affix a nut thereto, marked c, as the drawings represent.

The letters s represent leaden or iron balls, placed in the chambers of the shell, and the dotted marks adjoining the same represent the powder.

Fire is communicated to the powder in the respective chambers of my shell through the hollow rod C and the small apertures a.

The fire is communicated by means of fuse, inserted in the rod and in the openings leading to the respective chambers of the shell.

I pack the bottom of the shell, around the rod and above the leaden cap, with oakum, or other suitable material, and I also pack the spaces between the balls or shot in the chambers with sufficient oakum to prevent the balls from rubbing against each other, or igniting the powder.

Great care should be taken in loading the shell, in order to prevent the leaden cap from being pressed inward. This may be accomplished, to a great extent, by judicious packing, as above described.

What I claim as my invention, and desire to secure by Letters Patent, is—

A projectile, having cylinder A, cap B, rod C, and cap H, constructed and arranged substantially as specified.

In testimony that I claim the above, I have hereunto subscribed my name, in the presence of two witnesses.

JOHN D. RICHARDS.
